UNITED STATES PATENT OFFICE.

HERMAN W. LONG, OF EDNA, KANSAS.

SEPARATOR.

Application filed December 19, 1921. Serial No. 522,399.

To all whom it may concern:

Be it known that I, HERMAN W. LONG, a citizen of the United States, residing at Edna, in the county of Labette and State 5 of Kansas, have invented certain new and useful Improvements in Separators, of which the following is a specification, reference being had therein to the accompanying drawing.

10 This invention relates to certain new and useful improvements in separators for separating moisture of any kind, such as gas, oil or water from gases and is especially adapted to be used for separating liquids 15 from the natural gas, the object being to provide a separator which is automatic in its operation, the fluid laden gas entering an inlet and passing out an outlet while the liquid drops to the bottom of the separator 20 and is discharged through an outlet, the outlet being sealed by the liquid.

Another and further object of the invention is to provide a separator which can be used for separating any kind of liquid from 25 any kind of gas of any pressure from zero up to any amount.

A still further object of the invention is to provide a separator which is exceedingly simple and cheap in construction, the parts being 30 preferably formed of brass and wood and so arranged that the working parts of the separator can be readily removed for repairing.

A still further object of the invention is 35 to provide a separator in which the liquid is maintained at a predetermined height within the receptacle of the separator by a float which automatically releases the liquid after it rises beyond the predetermined level.

40 Other and further objects and advantages of the invention will be hereinafter set forth and the novel features thereof defined by the appended claim.

In the drawing I have shown a vertical 45 section through a separator constructed in accordance with my invention and comprises a rectangular receptacle 1 having an open end surrounded by a flange 2 on which is bolted a cover or face plate 3 by bolts 4. 50 The top of the receptacle is provided with a threaded opening 5 into which is screwed the threaded lower end of a cylindrical casing 6 which is provided with a threaded upper end 7 over which is screwed a cap 8 provided with a threaded bore 9 to which is connected a threaded outlet pipe 10.

The wall of the cylindrical casing 6 is provided with a bore 11 through which extends an inlet pipe 12, the end of which is closed by welding the same to the wall of 60 the casing at 13. The pipe 12 is welded in the bore 11 and is provided with a threaded outer end to which the moisture laden gas conduit is adapted to be connected. The pipe is cut away at 14 on its underside in 65 order to allow the liquid in the moisture entering the same to fall downwardly while the gases rise and pass out of the outlet 10.

Secured to the cover or face plate 3 by a brass bolt 15 is a valve casing 16 provided 70 with a vertical bore 17 enlarged to form a chamber 18 at its lower end, which is closed by a threaded plug 19. The top of the chamber is provided with a conical valve seat 20 adapted to be engaged by a conical 75 valve 21 carried by a valve stem 22 which is slotted at 23 in which is pivotally mounted the end of a lever 24 pivoted at 25 in the valve casing 16, said lever being preferably 80 formed of brass and of sufficient length to hold the valve 21 tightly against its seat 20.

The valve stem is annularly reduced as shown at 26 which forms an annular chamber 27 having inlet ports 28 formed by horizontal bores, said ports being of such a size 85 as to prevent foreign matter from entering the chamber 27. The wall of the chamber 18 of the valve housing is provided with a threaded bore 29 in alignment with bore 30 formed in the face plate and into which 90 is adapted to be screwed the threaded end of an outlet pipe 31, said pipe having a threaded outer end, on which is mounted a nut 32 adapted to engage a gasket for 95 securely fastening the outlet pipe 31 in position.

The outlet pipe is adapted to be connected to a conduit of any kind for conveying the collected fluid away from the separator. The upper end of the vertical 100 bore 17 in the valve casing is closed by a plug 33 and it will be seen that by this construction that when the cover plate is removed, the valve will be carried thereby so that it can be inspected and by removing 105 the plug 19 and the pivots of the lever 24, the valve will drop downwardly in order to allow the valve seat and valve to be refaced.

Arranged within the cylindrical casing 6 110 is a cylindrical float 34 preferably formed of cypress wood which is provided with a

vertical bore 35 in which is arranged a brass pipe 36 having an internally threaded upper end into which is screwed a bolt 37 which engages a square plate 38 arranged 5 on the top of the float 34.

The lower end of the pipe 36 is internally threaded and screwed into the same is the threaded stem 39 of a clevis 40 through 10 which the free end of the valve operating lever 24 is adapted to extend. The cylindrical float is mounted on pins 41 for holding the same in the cylindrical casing which limits the downward movement of the same.

The chamber 1 is provided with a threaded opening 42 herein shown closed by a plug 43 and by removing this plug and connecting the same to a manifold in one or more of a series of separators and by connecting 15 the inlet pipe and outlet pipe by manifolds, a series of separators can be connected up 20 and operated in a similar manner to the operation of the device when operated as a unit.

In the drawing I have shown the parts 25 as being described as being formed of brass or wood, both materials being impervious to the action of salt water; however, I do not wish to limit myself to the construction 30 of the separator of any particular kind of material as I am aware that this material can be changed to suit the nature of the gaseous fluid being separated.

In the operation of the device, the separator is arranged in a gas main and as the 35 gas enters the inlet pipe 12 the liquid carried thereby condenses or falls into the receptacle 1 and the gas rises and passes out the outlet 10. As the liquid accumulates 40 in the receptacle 1 and enters the casing 6, the float rises and as the float is connected to the valve through the medium of the lever 24, the valve 21 is forced off its seat, which allows the liquid to pass through the open-

ings 8 into the chamber 27 and from there into the chamber 18 and out the outlet pipe 45 31.

When the liquid drops to such a level that the lever is not affected by the float, the weight of the lever draws the valve 21 back 50 into closed position so as to stop the flow of liquid from the receptacle and it will be seen that these parts are working in the liquid at all times and that the liquid outlet is closed at all times so as to prevent 55 any gas escaping therethrough.

From the foregoing description it will be seen that I have provided a separator which is automatic in operation as the moisture laden gas in its passage through the separator deposits the liquid and allows the 60 gas to flow out an outlet at the top, the accumulating liquid being discharged automatically by a valve operating through the medium of a float.

What I claim is:—

A separator for the purpose described comprising a casing having a removable cover plate at one end thereof provided with an outlet pipe, a valve casing carried by said cover plate within said casing provided with a horizontally disposed inlet port and a horizontally disposed outlet port in communication with said outlet pipe, a vertically movable valve stem mounted in said valve casing provided with a valve at its 75 lower end, said stem being annularly reduced in alignment with said inlet port, a weighted lever mounted in said valve casing having a pivotal connection with the upper end of said valve stem for normally holding said valve in closed position, a float mounted in said casing and a loose connection between said float and said lever.

In testimony whereof I hereunto affix my signature.

HERMAN W. LONG.
